CLAIM

An ornamental design for a western saddle cover, as shown and described.

DESCRIPTION

FIG. 1 is a perspective view of a western saddle cover showing our new design;

FIG. 2 is a right side elevational view thereof, the opposite side being a mirror image of the right side shown;

FIG. 3 is a rear elevational view thereof;

FIG. 4 is a front elevational view thereof;

FIG. 5 is a top plan view thereof; and,

FIG. 6 is another rear elevational view thereof showing the stirrup cover open.
